United States Patent Office

Des. 190,750
Patented June 27, 1961

190,750

WALL-MOUNTED CLOCK

Frederic Marti and Georges Braunschweig, both of La Chaux de Fonds, Switzerland

Filed July 27, 1959, Ser. No. 56,939

Term of patent 14 years

Claims priority, application Switzerland Feb. 23, 1959

(Cl. D42—7)

FIGURE 2 is a view from the left side;

The dominant features of the design reside in the portions shown in full lines.

We claim:

The ornamental design for a wall-mounted clock, substantially as shown and described.
